UNITED STATES PATENT OFFICE.

ALFRED MARTIN, OF ROCKFORD, ILLINOIS.

FURNACE.

1,103,888.

Specification of Letters Patent. Patented July 14, 1914.

Application filed October 20, 1913. Serial No. 796,294.

To all whom it may concern:

Be it known that I, ALFRED MARTIN, a citizen of the United States, residing at Rockford, in the county of Winnebago and 5 the State of Illinois, have invented certain new and useful Improvements in Furnaces, of which the following is a specification.

This invention relates to warm-air furnaces.

10 The object of my invention is to provide such a furnace with a casing or jacket which may be easily opened or disassembled to give access to the warm-air chamber and to the heater, for the purpose of cleaning said 15 chamber and for repairing the heater.

A further object is to construct said casing in the manner of an adjustable frame and 20 detachable or movable casing-sections co-operating therewith, whereby the casing structure may be adapted to meet readily, various designs of furnaces.

It is my object also to construct a casing frame for carrying the above-mentioned detachable sections, which frame, after said 25 sections have been removed or moved from their normal position to give access to substantially the entire area of warm-air chamber, will support the furnace hood and its pipe-connections without causing derangement of same, this frame structure presenting an open web-like appearance.

These features coöperate in giving a furnace having high sanitary qualities and one which gives very efficient service because of 35 the fact that it can be easily maintained clean and its air passages unobstructed; and further, one which reduces expenses in upkeep, because when repairing is needed for the heater it is accessible without the great 40 expense of tearing down a fixed and integral furnace casing.

In furnace structures now in common use it is the custom to provide a casing for 45 enclosing the heater, the casing of such an integral structure that when, because of various defects that occur within the casing either to the warm-air chamber or to the furnace, it becomes necessary to gain access to said chamber or to repair said heater an 50 often difficult and expensive task is presented because the fixed casing structure must be torn down to repair the injury in-

side and rebuilt again when assembling. For this reason the fact is prevalent that 55 very few furnaces are maintained in proper working order to give efficient service. And because of dust, lint and other dirt particles accumulating within the warm-air chamber, the passages thereof become so restricted that the air circulation is greatly impeded, 60 and more important, such circulation because of said dirt accumulations is reduced to a very unsanitary state.

In my improved furnace structure embodying novel features above set forth, it is 65 evident that the defective features of integrally constructed casings and such as are difficult to disassemble, are entirely eliminated.

In the accompanying drawings: Figure 1 70 is a view in elevation of my improved furnace structure, portions thereof being shown fragmentary to illustrate more clearly the structure. Fig. 2 is a plan sectional view through the furnace as taken on the line 75 2—2 of Fig. 1. Fig. 3 is a detail sectional view taken on the line 3—3 of Fig. 1. Fig. 4 is a detail sectional view taken on the line 4—4 of Fig. 1. Fig. 5 is a horizontal detail sectional view as taken on the line 5—5 of 80 Fig. 1. Fig. 6 is a detail view in perspective of an end of a supporting-bar.

The heater 6 of the furnace may be of suitable structure and in this instance I have illustrated the heater with an associated furnace-front 7 having a fire-door 8 and ash-pit door 9, said furnace-front extending from a base 10 to a horizontal top ring 11 which is partly supported thereby. The furnace-front has flanges 12 extending 90 lengthwise at its sides, and a middle ring 13 has its ends bolted thereto, thus partly supporting said ring. Said top and middle rings are of similar construction, being shaped in cross-section with a vertical portion 14 forming the ring, and an outwardly extending flange 15, the outer sides of the ring forming casing receiving faces. A plurality of vertical supporting bars 16 spaced apart about the rings are interposed between the rings 11 and 13 and ring 13 and the base, to provide support for said rings and also means for attaching casing sections thereto. Said bars, upper and lower

are of similar structure. Each are formed of a flat body portion 17 having a central lengthwise extending rib 18, the ends of the bars being recessed transversely at 19 forming sockets 20 which leave the bar ends bifurcated whereby said bar bifurcated ends may fittingly engage the rings by receiving the rings in their sockets and recessed portions 19, this construction allowing the bars 5 to be moved sidewise independently by sliding movement of the bars upon the ring as a track-way, when assembling and fitting the casing-structure and also when it is desirable for any other purposes of adjustment, 10 this construction at the same time maintains the bars in supporting connection with the rings since the sides of the sockets 20 and recesses 19 hold the bars from displacement out of their operative position. 15 I have shown the casing divided into six sections (the furnace-front constituting one) by four of these bars, and the bars being bolted to the rings in a set position; but it is evident that any suitable number of 20 divisions may be made and of suitable width by the use of a greater or less number of bars, since the bars are slidably mounted upon the rings, as above mentioned. Casing-sections 21 of sheet material are made to close 25 the open spaces between the bars, their ends abutting the flanges 15 of the rings and their sides being associated with the bars, and they are secured in position by holding-strips 22 located on their outer sides and 30 being bolted to the bars. This holding means is adapted to secure the sections in place to provide a close fitting casing and one in which the sections can be easily removed, and it will be noticed that the outer 35 face of the bars that receive the casing sections are coincident with the outer face of the rings 11 and 13, thereby permitting a continuous casing receiving face between said members. In some furnaces the furnace-front 7 does not extend up to the top 40 ring or partition, therefore the intermediate space above said front could be provided with a detachable section such as has been described. Attached to the inner sides of 45 said sections are corrugated linings 23 which provide dead-air space to break the chill of the outer casing. 50 The manner in which I have herein shown the bars adjustable and the casing sections attached thereto might be deviated from to procure the equivalent result; and the sections might be hinged or provided with catch engagements with the bars. It might be desirable to eliminate the middle ring 13, 55 thereby having but single bars extending from the base to the top ring, or have a portion of the casing of integral structure and a portion extending around the casing of sectional structure; and it is evident that 60 this structure of horizontal rings, bars and

sections can be made into a casing in such various forms as to suit the most diversified requirements.

A chimney opening 24 extends through one of the casing sections and a cold-air inlet, not shown, may be entered through one of the lower sections. 70

The hood 25 fits upon the top ring, carries the usual distributing-pipe connections 26, and is formed with an open top 27 having a 75 rolled edge. A crown 28 fits in said opening with a rolled edge abutting that of the hood, and said crown is formed with a top 29 and a bottom lining 30 spaced therefrom to form a dead-air space, the bottom lining 80 being conical in shape to deflect the rising air to the sides and into the distributor-pipes.

With a furnace embodying a structure of casing of the above character, it will be 85 readily seen that when dirt or refuse accumulates in any portion of the warm-air chamber, that there is no difficult task in removing the necessary casing sections to gain access to said obstructions. Often 90 heaters become cracked and in order to repair same, with the common form of integral and fixed casing structures much more time and labor is spent in removing the casing to get at the damaged part than 95 there is expended in repairing the damage. Furthermore, substantially the whole casing must be removed, while in my improved structure only the sections adjoining the injured part are necessary to be removed. 100 It will also be noticed that when all the sections have been removed the distributing-pipes have not been deranged, but the hood 105 remains intact and supported by the bars; that the bar structure presents a web-like framework subject to be adjusted, and exposing entirely the heating structure of the furnace and also making the warm-air chamber entirely accessible; and that with the removal of the crown the accessibility 110 to the inner parts is further presented.

I claim as my invention:

1. In a furnace, an outer casing including spaced upper and lower casing-members, a plurality of spaced vertical supports, each having a socket therein at its opposite ends, said supports being in supporting engagement with said casing-members by the latter being received in said sockets, whereby the supports may be moved sidewise upon 115 the casing-members and be retained from lateral displacement, and casing-sections detachably mounted and interposed between adjacent supports. 120

2. In a furnace of the character set forth, the combination of spaced upper and lower horizontal peripherally extending casing members, vertical spaced supporting members interposed between said casing members for supporting the upper member, said 125 130

- supporting members having their ends connected with said casing members in such a manner that the vertical members are adjustable sidewise and are held during their 5 sidewise movement from breaking their supporting connections between the upper and lower members, and casing sections interposed between adjacent supporting members and being detachably connected thereto.
- 10 3. In a furnace of the hot air type, having a distributing-pipe hood, a supporting connection upon which the hood rests, devices for supporting said supporting connection, including a plurality of spaced vertically disposed supporting members each connected to said supporting connection, and mounted in such manner that they may be moved sidewise to different positions without breaking their supporting connection with 15 the hood, and casing sections interposed between adjacent supporting members and detachably connected thereto.
- 15 4. In a furnace, a heater, and a casing about the heater comprising a top portion having a plurality of conduit outlets, a horizontally disposed casing-frame portion, a plurality of vertical members mounted upon said casing-frame portion and being in connection with said top portion for 20 supporting same in position, the connection between said vertical members and the top portion and casing frame being such that the vertical members may be moved sidewise to different positions to effect different 25 spacing therebetween without destroying their supporting connection between the top portion and casing frame, and detachably mounted casing-sections interposed between 30 35
- adjacent vertical members whereby any one of the casing-sections may be detached to 40 permit access to the casing interior.
5. In a furnace of the character set forth, the combination of a heater, and a casing thereabout including an upper and lower track-way extending about a portion of the 45 casing, a plurality of vertical members mounted movable along said track-ways to permit different spacing between said vertical members, said vertical members serving as a means for supporting the upper 50 track-way in position, and the mounting of said members in connection with the track-ways being such that the members are held at all times from lateral displacement relative to the track-ways.
- 55 6. In a furnace of the character set forth, the combination of a heater, a casing thereabout including upper and lower ring-members, a plurality of vertical supporting bars 60 interposed between said ring-members, having bifurcated ends which are associated with the ring-members by the latter being received in the recesses of the bar ends to permit the bars to be slidable along the ring-members without breaking their association therewith, and casing-sections interposed between adjacent bars and being detachably connected thereto.
- 65 In testimony whereof I have hereunto set my hand in presence of two subscribing witnesses:
- 70 ALFRED MARTIN.
